Primary Examiner — L. Martinez(74) *Attorney, Agent, or Firm* — Buckley, Maschoff & Talwalkar LLC(57) **CLAIM**

The ornamental design for a bracelet, as shown and described.

DESCRIPTION

FIG. 1 is a top perspective view of a bracelet in accordance with the present design;

FIG. 2 is a bottom perspective view of the bracelet;

FIG. 3 is a front view of the bracelet;

FIG. 4 is a rear view of the bracelet;

FIG. 5 is a first side view of the bracelet taken ninety degrees from the front view;

FIG. 6 is a second side view of the bracelet taken ninety degrees from the front view;

FIG. 7 is a top view of the bracelet; and,

FIG. 8 is a bottom view of the bracelet.

The broken lines in the drawings represent portions of the bracelet that form no part of the claimed design. The other broken lines indicating text represent environmental subject matter only and form no part of the claimed design.

1 Claim, 4 Drawing Sheets(56)
